[57] CLAIM

The ornamental design for a merchandising display unit for doors, as shown and described.

DESCRIPTION

FIG. 1 is a perspective view of the merchandising display unit for doors showing the new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken line showing of environmental structure shown in FIGS. 1, 2, 3, 4, 6, and 7 is for illustrative purposes only and forms no part of the claimed design.
